(57) **CLAIM**

The ornamental design for a sprayer, as shown and described.

DESCRIPTION

FIG. 1 is a perspective view of an example embodiment of a sprayer in accordance with our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the sprayer shown in FIG. 1 and illustrating an example environment in which the sprayer may be used, whereby the sprayer is releasably coupled to a handle of a container;

FIG. 9 is a perspective view of another example embodiment of a sprayer in accordance with our new design;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof; and,

FIG. 16 is a perspective view of the sprayer shown in FIG. 9 and illustrating an example environment in which the sprayer may be used, whereby the sprayer is releasably coupled to a handle of a container.

The details shown in broken lines in the example embodiments are for illustrative purposes only in those embodiments and form no part of the design claimed with respect to those embodiments.

1 Claim, 14 Drawing Sheets
